COVER CLIP

Filed Dec. 8, 1924

Fig. i

Inventor
Metta O. M. Brown
By Bair, Truman & Atty. 1146.

UNITED STATES PATENT OFFICE.

METTA IDA M. BROWN, OF SIOUX CITY, IOWA.

COVER CLIP.

Application filed December 8, 1924. Serial No. 754,537.

My invention relates to a fastening clip especially adapted to the purpose of securing in place the covers of a child's or other bed, or to hold automobile robes in place.

5 An object of my invention is to provide such a clip which is of simple, durable and inexpensive construction.

Another object is to provide such a clip which may be readily attached to, or detached from, the rail of a bed.

10 More specifically, it is my object to provide such a clip having a pair of jaws hinged to a supporting bracket at spaced points so that when swung on their axes the engaging 15 ends of the jaws will move relative to each other.

A further object is to provide such a pair 20 of jaws hinged to a supporting bracket and having a sliding connection with each other such that movement of one jaw will cause corresponding movement of the other jaw.

A still further object is to provide a cover 25 clip as mentioned adapted to be attached to a bed rail in such a manner that gravity normally retains the jaws in open position, and the hooking of the edges of the bed 30 covers under one of the jaws and subsequent raising of those portions of the covers will operate to automatically close the jaws upon the covers, thereby allowing very rapid manipulation of the clips when securing them to the covers.

With these and other objects in view, my 35 invention consists in the construction, arrangement and combination of the various parts of my device, whereby the objects contemplated are attained, as hereinafter more fully set forth, pointed out in my claim and illustrated in the accompanying drawings, 40 in which:

Fig. 1 is a sectional view taken transversely through a bed rail, a portion of the adjacent bed slat and springs being shown, and my improved cover clip, shown in inoperative position in full lines and in operative 45 position in dotted lines, attached to the rail.

Fig. 2 is a perspective view of the rail with the clip attached in inoperative position.

I have used the reference character 10 to indicate generally a bed rail of the ordinary type, which is L-shaped in cross section. Supported on the horizontal arm of the rail, 50 10 is one end of a bed slat, 11, which serves

to receive the springs, 12. The covers of the bed are not shown in full lines.

My improved clip comprises a bracket, A, having the post, 14, which is provided with spaced sleeves, 15 and 16, at its outer 60 end and intermediate of its length, respectively. The sleeves, 15 and 16, may be formed in the metal of the post, 14, by any of the well-known methods, or may be in the form of separate bushings soldered or brazed 65 thereto.

The bracket is provided with an opening, 17, which serves to retain a strap, 18, used to secure the bracket, A, to the bed rail. The strap, 18, may be of any material such as 70 leather or fabric.

In the bushing, 16, are secured the ends, 22, of the lower jaw, B. The jaw, B, is formed of a single piece of wire, having the jaw proper, 23, bent to form teeth, 24, 75 extending into a space enclosed by the side members, 25 and shoulders 26, of the jaw. The side members, 25, are bent at right angles to the jaw portion, 23, and the shoulders, 26, at right angles to the side 80 members, 25, in the same plane with the side members, 25, and jaw, 23.

The middle of the jaw, B, is thence bent at right angles to the plane of the members, 23, 25 and 26, to form the arms, 27, having 85 on their ends the inturned lugs, 22.

The upper jaw, C, is formed of a single piece of wire, having a jaw proper, 28, bent to form the outwardly-extending teeth, 29, thence bent to form the side members, 30, 90 thence bent inwardly as at 31, and substantially parallel with the side members, 30, to form the arms, 32, which are spaced within the arms, 27, of the jaw, B. The arms, 32, are looped about the arms, 27, at a point 95 near the lugs, 22, when the jaws are in open position.

The loops I have referred to by the reference numeral 33.

From thence the arms, 32, are continued 100 in the same direction as at 34, and bent inwardly to form the lugs, 35, received in the ends of the sleeve, 15.

As shown in the drawings, the jaws normally assume a position inclined downwardly and outwardly. The down movement of the jaws is limited by the engagement of the loops, 33, with the bracket. In this position the jaws proper, 29 and 23, are separated, as shown. 110

When the housewife wishes to make the beds, after spreading the covers in position she grasps the edges of the covers at a point on either side of the clip and inserts the intervening portion between the jaws, B and C. Hooking the covers under the jaws, C, she pulls upwardly and the jaw, C, then will swing around its pivot, carrying the jaw, B, with it by virtue of the sliding connection of the loops, 33. As the jaws are swung upwardly they approach each other, the jaw, C, being of proper size to enter the open jaw, B. The covers, indicated at 36 in dotted lines in Fig. 1, will be effectively secured between the jaws, and any pull upon the covers will only tighten the grip thereof.

It will be seen that the device can be readily attached to a child's bed or the bows of a vehicle top. When applied to a bed ordinarily two of the devices are used—one at each side of the foot of the bed. In the case of a crib, the device may be used at all four corners.

Some changes may be made in the construction and arrangement of the parts of my invention without departing from the

real spirit and purpose of my invention, and it is my intention to cover by my claim any modified forms of structure or use of mechanical equivalents which may be reasonably included within its scope.

I claim as my invention:

A cover clip comprising a bracket, a pair of jaws hinged to said bracket on axes 35 spaced from each other such that hinging movement of the jaws simultaneously in one direction will separate them, while hinging movement of the jaws simultaneously in the opposite direction will bring 40 them together, each of said jaws comprising a jaw proper and spaced arms connecting said jaws to the bracket, the spaced arms of one jaw being looped about the arms of the other jaw to provide a sliding connection 45 such that hinging movement of one jaw will automatically induce corresponding hinging movement in the same direction of the other jaw.

Signed at Sioux City, in the county of 50 Woodbury and State of Iowa, this 11th day of March, 1925.

METTA IDA M. BROWN.
